MAXIMILIAN H. VON PAGENHARDT, OF ST. LOUIS, AND WARD T. BARKER, OF KANSAS CITY, MISSOURI, ASSIGNORS, BY DIRECT AND MESNE ASSIGNMENTS, OF ONE-THIRD TO MAXIMILIAN H. VON PAGENHARDT, OF ST. LOUIS, MISSOURI, AND TWO-THIRDS TO B. P. LIENTZ OIL FURNACE COMPANY, OF KANSAS CITY, MISSOURI, A CORPORATION OF DELAWARE.

BAFFLE FOR BOILERS.

Application filed May 14, 1923. Serial No. 638,749.

This invention relates to improvements in baffles for water tube boilers, and particularly to a device of this kind by the use of which the products of combustion within a boiler may be controlled in a manner to produce much greater heating efficiency than was possible with any of the baffling arrangements heretofore used.

As is well known, many different methods have been employed to baffle, or control, the hot gases emanating from the burning fuel within the furnace of a steam boiler of the water tube type, so that said gases may act upon the water tubes in a manner to transmit the maximum amount of heat thereto, but none of these methods have been entirely successful, despite the fact that some of them have been in use for many years.

One of the methods of baffling heretofore employed is the so called vertical method which involves the use of a plurality of baffles arranged at approximate right angles to the water tubes, and spaced apart one from the other. In following out the vertical method, the hot gases pass and repass transversely of the nest of tubes to heat the water within said tubes, but one of the objections to this method is that each tube is located in a plurality of zones of different temperatures.

Another method of baffling used is the horizontal method which involves the use of a plurality of baffles extending longitudinally of the water tubes and located one above the other. While the horizontal method functions with greater efficiency than the vertical method, in most types of water tube boilers, still it is not entirely successful due to the fact that the shrinkage of the gases at lessening temperatures is not taken into consideration, consequently a great loss of heat is suffered. Another disadvantage in connection with the horizontal method is that it is necessary to omit a row of water tubes to permit the introduction of each intermediate baffle, thus reducing the heating surface of the boiler and permitting the gases to short circuit.

The baffle disclosed in the present application is intended for use in boilers provided with a pair of horizontal baffles and provides means whereby the hot gases within a boiler may be scientifically controlled, and as the passageways through which said gases pass

are reduced in size at the points where the gases have been reduced in volume, due to 55 their shrinkage at lessened temperatures, the maximum heating efficiency is obtained from said gases throughout their passage through the boiler.

With the foregoing and other objects in view, the invention comprises the novel construction, combination and arrangement of parts hereinafter more specifically described and illustrated in the accompanying drawings wherein is shown the preferred embodiment of the invention. However, it is to be understood that the invention comprehends changes, variations and modifications which come within the scope of the claims hereunto appended.

Fig. I is a vertical section through an ordinary boiler of the water tube type, showing our improved baffle and associated therewith, portions of said boiler being shown in elevation.

Fig. II is a horizontal section on line II—II of Fig. I, portions of the housing being omitted.

Fig. III is a fragmentary cross section through the tube nest of a boiler, showing our 80 baffle in place therein, a fragment of the steam chest of the boiler being shown above said nest of tubes.

Fig. IV is a horizontal section of a section of our improved baffle, fragments of the adjacent sections being associated therewith.

Fig. V is a horizontal section of one of the rearmost sections of our baffle.

Fig. VI is a modification of our invention wherein a pair of vertical baffling members 90 is employed.

Fig. VII is a modified form of our invention wherein a single inclined baffling member is employed instead of the V-shaped baffling member as illustrated in the preferred construction.

In the drawings, A designates a boiler provided with the usual housing B of brick-work or other fire-resisting material. The boiler illustrated in the drawings is provided with a burner C whereby fuel is introduced into, and is burned within, the housing B. Arranged above the housing B is the tube nest E which comprises a front header F, a back header G, and a plurality of tubes 105 H which are connected to said headers F and

G in the usual manner. The tube nest E is supported by the housing B in the ordinary way, and arranged above said tube nest in the usual steam chest J.

5 The foregoing is a very brief description of the boiler illustrated in Fig. I of the drawing, but because said boiler is of the usual construction, and in view of the fact that said boiler forms no part of the present invention, we do not deem it necessary to describe the same in detail.

Arranged longitudinally of the tube nest E, adjacent to the lower portion thereof, is baffle 1 which comprises the usual baffle used in boilers of the type illustrated, said baffle being composed of a plurality of elongated members, each of which is inserted between a pair of adjacent water tubes H (Fig. III). The baffle 1 fits closely against the back header G and the front end of said baffle is spaced a considerable distance from the front header F to provide a passageway 2 for the hot gases arising from within the housing B.

Arranged longitudinally of the tube nest E adjacent to the upper portion thereof is a second baffle 3, said last mentioned baffle being similar to the baffle 1 excepting in certain particulars which will be hereinafter pointed out.

30 It will be noted by referring to Fig. III of the drawing that the individual water tubes of boilers of the type illustrated are so arranged relative to each other that diagonal spaces between the tubes, or "alleys" as they are called, are produced. These "alleys" are at angles of approximately 45° to 60° to the horizontal and extend in both directions.

4 designates our improved baffle which comprises a pair of baffling elements, each of which is composed of a plurality of baffle sections as shown in Figs. II and IV. The baffle sections are each provided with longitudinal edges 4' which are so shaped as to cooperate with baffle sections having similarly shaped longitudinal edges whereby said sections may be assembled to produce a plate-like baffle member having comparatively gas-tight joints.

50 In use each of the baffle members is introduced into one of the diagonal "alleys" between certain of the water tubes H, and as will be seen by referring to Fig. III the lower edges of said baffle sections are formed at the proper angle relative to the side faces thereof, so that a comparatively tight joint will be obtained between said baffle sections and the side wall of the housing B. A complete baffle 4 preferably comprises a pair of baffle members, said baffle members being arranged relative to each other so that they form what is approximately an inverted V, and when said complete baffle is in place within the boiler the space between the baffles 1 and 3 is divided into a plurality of passageways, the center or larger one of which we

have designated by the reference character X, the space on the left of said passageway X by the reference character Y, and the space on the right of the space X by the reference character Z.

70 The upper baffle 3 already referred to is divided into different parts by the baffle members of the baffle 4 (Fig. III) and a peculiarity of said baffle 3 will now be pointed out. Located in the center of the baffle 3 is a longitudinal baffle member which we have designated by the reference character 3'. The baffle member 3' fits firmly against the two adjacent water tubes H and said baffle member also firmly contacts with the front header F and the back header G, and because the baffle members of the baffle 4 are in firm contact with the water tubes between which the baffle member 3' is located, it is apparent that a comparatively gas-tight upper wall is provided for the space X. The elongated baffle members of the baffle 3 which form the top wall of the spaces Y and Z, like the members 3', contact firmly against the back header G, but instead of extending to and contacting with the front header F, said baffle members stop short of said front header to produce passageways 5 and 6 between said spaces Y and Z and the space above the baffle 3.

85 The baffle 4, as shown most clearly in Fig. II, contacts firmly with the front header F of the boiler, but the rear end of said baffle 4 stops short of the back header to provide a passageway 7 between the space X and the space Y and a passageway 8 between the space X and the space Z.

90 In the use of a boiler provided with our improved baffle the flame and hot gases being emitted from the burner C follow the course indicated by the arrows within the housing B in Fig. I, and as said gases pass longitudinally of those water tubes which are located below the baffle 1, the water within said tubes will be heated. The gases then pass through the opening 2 and into the passageway X, and as said gases pass longitudinally of the water tubes within said passageway X, the water in said tubes will be heated. When the gases passing through the passageway X reach the rear end thereof some of said gases pass through the opening 7 into the passageway Y, and some of said gases pass through the opening 8 into the passageway Z (Fig. II). The gases which have passed into the passageways Y and Z then pass longitudinally of the water tubes within said passageways, and said gases then escape through the openings 5 and 6 and pass from the boiler in the usual way.

100 As already suggested, the hot gases shrink as temperature is lessened and heretofore much heating efficiency was lost due to the fact that the same size passageway was provided for the gases throughout their passage through the boiler. In the use of our im-

proved baffle this loss of efficiency is prevented because the sizes of the various passageways are arranged in proportion to the volume of gases passing therethrough. It is plain in the use of our invention that said gases will be thoroughly mixed as they pass from one passageway to the other.

Each baffle section of the baffle 4 is provided with a steam passageway 10 which is open at the top of said baffle and extends downwardly therein to a point adjacent to the lower portion thereof, as shown in Fig. IV and by dotted lines in Fig. I. The walls of the passageways 10 extend outwardly beyond the faces of the associated baffle section and the walls of each of said passageways are provided with inclined portions 11. Formed through the inclined portions of the walls of the passageways 10 are apertures 12, said apertures being inclined relative to the face of the baffle section, as shown most clearly in Fig. IV.

Arranged adjacent to the upper edge of each baffle member of the baffle 4 is a steam conductor 13, said conductors being extended longitudinally of said baffle members, and each of said conductors is provided with a plurality of nipples 14 which are connected to said conductor so that they are in communication with the passageway therethrough. The lower end of each of the nipples 14 is connected to one of the baffle sections in such manner as to be in communication with the passageway 10 thereof. One end portion of each of the steam conductors 13 extends beyond the boiler to a suitable steam supply and each of said conductors is provided with a controlling valve 15. Located adjacent to the rearmost end of each baffle member of the baffle 4 is a pipe 16 provided with perforations 17, said pipe being arranged longitudinally of said rearmost ends of said baffle members (Fig. I). The pipes 16, like the passageways 10, are in communication with the passageways through the steam conductors 15 through the use of nipples 18, and the lower ends of the passageways through said pipes 16 are closed in any suitable manner.

In the use of a boiler equipped with our improved baffle and soot-blowing device, assume that soot has accumulated on the baffle members, and it is desired to remove same. In this event, the valves 15, are opened permitting steam to pass through the conductor 13 and nipples 14 into the passageways 10 in the baffle sections, and from said passageways 10 forcibly through the apertures 12 into the nest of water tubes, said apertures being so located as to cause jets of steam to be directed through the "alleys" between the water tubes, thus obviating the danger of the force of said jets being broken by striking tubes comparatively close to the aperture from which said jet of steam is ejected. When the steam is directed into the passageways 10 in the baffle

section, it will also be directed into the pipes 16 and will pass from the apertures 17 therein to sweep the rear portion of the tube nest.

As has been stated, the apertures 12 in the baffle sections are inclined relative to the side faces of said baffle sections, and because of this arrangement the jets of steam will be discharged in the same direction as the direction of flow of the gases in passageway into which said jets are directed, thus eliminating any tendency for the jets of steam to retard the flow of gases.

A distinct advantage in favor of our baffle and soot-blowing device over those heretofore used is that it may be installed in an old boiler without tearing said boiler completely down; for instance, if it be desired to install our device in a boiler equipped with horizontal baffles, it is only necessary to introduce our device in place. To install our device in place in a boiler having vertical baffles, it would be necessary to replace said vertical baffles with horizontal baffles and then introduce our baffle in place.

Fig. VI illustrates a modified form of our invention wherein the baffle members are arranged vertically in the nest of water tubes instead of inclined as shown in the preferred construction. This arrangement is used where the "alleys" between the water tubes are vertical and horizontal instead of inclined at 45° or 60°.

Fig. VII illustrates a second modification wherein a single inclined baffle member is used instead of a pair of baffle members, as shown in the preferred construction.

We claim:

1. A baffle for water tube boilers provided with horizontal baffles extending the entire width of the boiler, comprising a pair of baffle members arranged between said horizontal baffles, said baffle members being arranged longitudinally of the boiler and being introduced between rows of water tubes whereby the space between said horizontal baffles is subdivided into a plurality of independent passageways, said baffle members being so arranged with respect to said horizontal baffles and to the side walls of the boiler as to provide means of communication between said passageways only at an end of the boiler.

2. A baffle for water tube boilers provided with horizontal baffles extending the entire width of the boiler, comprising a pair of inclined baffle members arranged longitudinally of the boiler and arranged between said horizontal baffles whereby the space between said horizontal baffles is subdivided into a plurality of independent passageways, said baffle members being so arranged with respect to said horizontal baffles and to the side walls of the boiler as to provide means of communication between said passageways only at an end of the boiler.

3. A baffle for water tube boilers provided

with horizontal baffles extending the entire width of the boiler, comprising a pair of inclined baffle member arranged longitudinally of the boiler and arranged between said horizontal baffles to produce a V-shaped baffle whereby the space between said horizontal baffles is subdivided into a plurality of independent passageways, said V-shaped baffle being so arranged with respect to said horizontal baffles and to the side walls of the boiler as to provide means of communication between said passageways only at an end of the boiler.

4. A baffle for water tube boilers provided with horizontal baffles, comprising a pair of inclined baffle members introduced between rows of water tubes of said boiler, said baffle members being so arranged between said horizontal baffles as to produce a V-shaped baffle whereby the space between said horizontal baffles is subdivided into a plurality of independent horizontal passageways, said V-shaped baffle being so arranged with respect to said horizontal baffles and to the side walls of the boiler as to provide means of communication between said passageways only at an end of the boiler.

5. A baffle for water tube boilers provided with horizontal baffles, comprising a pair of inclined baffle members introduced between rows of water tubes of said boiler, each of said baffle members being composed of a plurality of sections and said baffle members being so arranged between said horizontal baffles as to produce a V-shaped baffle whereby the space between said horizontal baffles is subdivided into a plurality of independent horizontal passageways, said V-shaped baffle

being so arranged with respect to said horizontal baffles and to the side walls of the boiler as to provide means of communication between said passageways only at an end of the boiler.

6. A baffle for water tube boilers provided with horizontal baffles extending the entire width of the boiler, comprising a baffle member arranged between said horizontal baffles, said second mentioned baffle being arranged longitudinally of the boiler and being introduced between rows of water tubes thereof whereby the space between said horizontal baffles is subdivided into a plurality of separate compartments, an end of said second mentioned baffle being spaced from an end wall of the boiler so as to provide means of communication between said passageways only at said end of the boiler.

7. A baffle for water tube boilers provided with horizontal baffles extending the entire width of the boiler, comprising an inclined baffle member arranged between said horizontal baffles, said second mentioned baffle being arranged longitudinally of the boiler and being introduced between rows of water tubes thereof whereby the space between said horizontal baffles is subdivided into a plurality of separate compartments, an end of said second mentioned baffle being spaced from an end wall of the boiler so as to provide means of communication between said passageways only at said end of the boiler.

In testimony that we claim the foregoing we hereunto affix our signatures.

MAXIMILIAN H. von PAGENHARDT.
WARD T. BARKER.
